UNITED STATES PATENT OFFICE.

JOSEPH RENÉ AYOTTE, OF CHICAGO, ILLINOIS.

HAND-TOOL.

1,349,553.

Specification of Letters Patent. Patented Aug. 17, 1920.

Application filed October 1, 1919. Serial No. 327,741.

To all whom it may concern:

Be it known that I, JOSEPH RENÉ AYOTTE, a subject of the King of Great Britain, residing at Chicago, in the county of Cook 5 and State of Illinois, have invented certain new and useful Improvements in Hand-Tools, of which the following is a specification.

The invention relates to improvements in 10 hand tools, such as wrenches, and the like.

One of the objects of the invention is to provide a neat, convenient and efficient tool that may be used as a wrench and for other similar purposes.

15 Another object is to provide a tool having an extension handle that can be elongated or contracted with ease and convenience and which may be made to reach and control objects that are otherwise inconveniently accessible, such as nuts, bolts or the like.

Another object is to provide a tool containing three concentric tubes, the two inner tubes being rotatably connected to 25 together and capable of axial extension, the outer tube serving as a jacket or supporting means to hold the tool while in use.

Another object is to deflect the outer end 30 of the tubular jacket and place therein a tool or bit holding socket to receive a bit or nut socket and connect the tool-holding socket with the rotatable tube by an universal joint.

Another object is to provide a head at 35 one end of the tool by which to rotate the inner tube to give motion to the bit holder or nut socket.

Another object is to provide a double, shiftable ratchet, between the handle head and the 40 rotatable tube, whereby the latter may be positively rotated to the right, or to the left, by shifting the ratchet controlling means, or the ratchet may be rendered ineffective by moving the shifting part to a 45 selected position.

Another object is to provide means for inserting and for holding hard grease within 50 the tool to lubricate the moving parts.

Other, further and more specific objects 55 of the invention will become readily apparent to persons skilled in the art from a consideration of the following description when taken in conjunction with the drawings, wherein:—

Figure 1 shows the tool with the handle partly elongated.

Fig. 2 shows the parts collapsed or occupying the shortest dimensions.

Fig. 3 is a central longitudinal section showing the various parts of the structure. 60

Fig. 4 is a transverse section taken on line 4—4 of Fig. 3.

Fig. 5 is a similar section taken on line 5—5 of Fig. 3.

Fig. 6 is a similar section taken on line 65 6—6 of Fig. 3.

Fig. 7 is a similar section taken on line 7—7 of Fig. 3.

Fig. 8 is a similar section taken on line 8—8 of Fig. 3.

In all the views the same reference characters are employed to indicate similar parts.

The outer holding tube or jacket 10 may be knurled, as at 11, to provide a better surface to be grasped by the hand, and serves as a means by which the tool may be supported in the hand of the operator. The lower free end of the jacket 10 is laterally deflected, as at 12, and contains a rotatable 75 tool-holding socket 13.

A rotatable tube member 14, concentric with the tube 10 and located therein, is provided on its end with means by which it is pivotally connected to the universal joint member 15. The coöperating joint member is connected to the end 16 of the socket part 13, so that the socket 13 may be rotated by rotation of the tube 14. The tube member 14 is axially slotted, as at 80 17, and a blade 18, fixed to the inner tube member 19 may be slid within the slot 17. The blade 18 is held in the tube 19 by means of a pin 20. When the tube 19 is rotated, the tube 14 is rotated thereby through the 85 instrumentality of the blade 18 which is within the slot 17 of the other tube member. When the tube 19 is moved axially, out of the tube 14, as shown in Fig. 1, the blade is still within the slot 17 and the tube 14 may, therefore, be rotated from any point, by the 90 blade 18, secured to tube 19. The upper end of the tube 19 contains a head 21 and on the inside of the head 21 is a tube 22, secured thereto by a pin 23. The upper part of the head 21, as at 24, is made hexagonal in 95 shape, over which a hexagonal ring 25 is freely slidable. The ring is cut away, at one of its angular surfaces, and a spring clip 26 is placed within the cut-away part to produce more or less friction with the parts 100 over which the ring 25 is slidable to cause it to remain in the position in which it is 105 110

placed. The upper face of the head 31 is provided with ratchet teeth 27 and a hexagonal ring 28 freely rotatable on the tube 22 and always within the slidable ring 25 5 is provided with corresponding ratchet teeth 30. Another head 31, forming part of the handle, is slidably mounted on the tube 22. The head 31 is hollow and contains an open coiled spring 33, secured in place on 10 tube 22 by pin 34, to hold the lower end 35 of the head 31 in intimate contact with the upper surface of the ring 28. The upper surface of the ring 28 is provided with ratchet teeth 36 that are inclined in the opposite direction to the ratchet teeth 27 and 15 30. Now when the ring 25 is in the position shown in Figs. 2 and 3, the head 31 may be rotated effectively, clockwise or to the right, to positively rotate the socket 13, and when rotated in the opposite direction the ratchet teeth 36 and 37 will move the head 31 outwardly against the resilient efforts of the spring 33. Now when the ring is moved axially into the upper position, shown in Fig. 1, the ratchet teeth 29 20 and 30 are free to perform their desired and intended function so that when the head 31 is rotated to the left, or anti-clockwise, the socket 13 is thereby rotated in the same direction, the head being moved outwardly 25 against the resilient action of the spring 33, when it is rotated to the right, so that by holding the ring 25 into either of the positions, the socket 13 may be positively rotated in either direction. If it is desired to 30 remove a nut from the bolt, then the ring 25 is moved upwardly, in the position shown in Fig. 1, and the ratchet teeth 27 and 30 will permit the head 31 to move freely to 35 the right and will positively move the socket 13 to the left. If it is desired to screw a nut onto a bolt, then the ring 25 is moved into the position shown in Figs. 2 and 3, whereupon the ratchet teeth 36 and 37 are free to 40 act. When the ring 25 occupies an intermediate position, covering both sets of ratchet teeth, then both of the ratchets are disabled and the socket 13 may be positively rotated in either direction by the rotation of the 45 handle head 31.

In the upper end of the handle head 31 is a screw 39 for securing in place a transversely extending rod 40, which serves as 50 convenient and removable means by which the head 31 may be rotated. The central portion of the rod is knurled, as at 41, for convenient location of rod 40 in the head and for offering a surface for contact with the inner end of the screw 39 to more securely hold the rod in place. The tube 19 is preferably grooved, as at 42, at intervals, so that when the screw 43 is backed out, the tube 19 may be drawn out of the surrounding co-operating tube member 14. The screw 60 43 is then set into one of the grooves, and

the extended parts are thus held in the position until it is desirable to contract them again, as shown in Fig. 2. This may be convenient when the bolt, nut, or screw desired to be operated upon, is located at a remote point and at such distance that it cannot be readily reached when the tool is in its contracted condition.

An orifice 45 is made at the lower end of the tube through which hard grease may be 75 forced, so as to lubricate the universal joint 16 and the other moving parts within the jacket 10. A similar orifice 46 is made in the head 31 through which hard grease or other lubricant may be inserted within the 80 head.

A socket 48 or other form of bit or nut holder may be inserted in the tool socket 13 and held in place by a screw 49, there being a groove 50 made in the socket 48 within 85 which the screw 49 engages for the purpose of holding it in its operative position. Any tool, other than the socket 48 may be inserted in the operative socket 13, such as a bit, drill, tap or the like.

When the tool is not in use, the rod 40 may be removed from the head 31 so that the device will occupy a relatively small space.

While I have herein shown a single embodiment of my invention for the purpose of clear disclosure, it will be manifest, to persons skilled in the art, that changes may be made in the general arrangement and configuration of the parts within the scope of 95 the appended claims.

Having described my invention, what I claim is:—

1. A tool of the character described, having in combination a tubular non-rotatable jacket; a bit holder in one end of the jacket; a two-part telescoping, rotatable tube, consisting of an inner and an outer member within said jacket, one member connected to the bit holder; a handle, rotatable on the outer end of the extendable tube member, outside of the jacket and a ratchet between the handle and the outer end of the extendable tube member.

2. A tool of the character described having in combination a tubular non-rotatable jacket; a bit holder in one end of the jacket; a two-part telescoping, rotatable tube, consisting of an inner and an outer member, within said jacket, one member connected to the bit holder; a handle rotatable on the outer end of the extendable tube member, outside of the jacket; a double ratchet between the handle and the extendable tube member and means to alternatively disable 125 one of the ratchets.

3. In a tool of the character described having in combination a tubular non-rotatable jacket, one end of which is laterally deflected; a bit holder in the deflected end 130

of the jacket; a two-part telescoping, rotatable tube, consisting of an inner and an outer member within the main body of said jacket; a universal joint connection in said jacket, between one member of the rotatable tube and said bit holder; a handle rotatable on the outer end of the other rotatable tube member; a rotatable ring, having a set of ratchet teeth on each of its ends, the teeth of the sets inclined in opposite directions; coöperating ratchet teeth on the adjacent end of said other rotatable tube member; co-operating ratchet teeth on the confronting end of the handle and means to hold the ring fixed with either set of teeth to permit operation of the other set.

4. A tool of the character described having in combinative association a tubular non-rotatable jacket, one end of which is laterally deflected; a bit holder in the deflected end; a rotatable element comprising two telescopic members, in the main body of the fixed jacket; a universal joint connection between said bit holder and one member of said rotatable element; a handle rotatable on the outer end of the other mem-

ber of said rotatable element, outside of the fixed jacket; a ratchet between the outer end of said member and said handle and a slideable connection between said element members whereby the member connected to the handle may be withdrawn from the jacket to increase the effective length of the tool.

5. A tool of the class described having an outer non-rotatable jacket; a rotatable tube axially fixed therein; a bit holder in the jacket connected to one end of the rotatable tube; an axially extensible member in said rotatable tube, rotatably secured thereto; a handle on said member; a ratchet member on the outer end of said extensible member; a ratchet member on the confronting end of the handle; an intermediate ratchet member arranged for coöperation with either of the first mentioned ratchet members and means for selectively securing the intermediate ratchet member rotatably with either of the other ratchet members to rotate the bit holder in opposite directions.

In testimony whereof I hereunto subscribe my name.

JOSEPH RENÉ AYOTTE.
